UNITED STATES PATENT OFFICE.

JOHN HENRY JENNINGS, OF GEORGETOWN, CONNECTICUT.

RAIL CONNECTING AND SUPPORTING MEANS.

1,382,424.

Specification of Letters Patent. Patented June 21, 1921.

Application filed April 20, 1921. Serial No. 462,896.

To all whom it may concern:

Be it known that I, JOHN H. JENNINGS, a citizen of the United States, and a resident of Georgetown, in the county of Fairfield 5 and State of Connecticut, have invented a new and Improved Rail Connecting and Supporting Means, of which the following is a full, clear, and exact description.

This invention relates to rail joints and 10 more particularly to connecting and supporting means for the meeting ends of a pair of rails.

The invention contemplates an effective means of connecting and supporting the 15 meeting ends of a pair of rails with a view of minimizing the jar incident to the passage of the wheels of the rolling stock over the rail ends, to prevent wear both on the rail heads at this point and a possible fracture or chipping of the wheels.

A further object of the invention resides in the provision of a supporting and connecting means for the meeting ends of rails which positively prevents creeping of the 25 same with respect to the ties.

A further object in view resides in the provision of a connecting and supporting means of the character described which eliminates the necessity of altering in any 30 manner the construction of standard rails which might tend to weaken the structure or add to the expense of manufacture of the same.

A still further object in view resides in the provision of a connecting and supporting means for the meeting ends of rails which is readily applicable to or removable 35 from the ties, and which when properly associated with the ties and rails provides a safe and efficient connection therebetween and eliminates the possibility of spreading 40 of the rails at their point of connection.

With the above recited and other objects in view the invention resides in the novel 45 construction, combination and arrangements of parts set forth in the following specification, pointed out in the appended claims and illustrated in the accompanying drawing, it being understood that variations and modifications which properly fall within the scope 50 of the appended claims may be resorted to when found expedient.

In the drawings—

Figure 1 is a longitudinal sectional view 55 through the connecting and supporting

means illustrating the same associated with the meeting ends of a pair of rails.

Fig. 2 is a transverse sectional view taken approximately on the line 2—2 of Fig. 1.

Fig. 3 is a similar view taken on the line 60 3—3 of Fig. 1.

Fig. 4 is a perspective view illustrating the chair members and bridge plate removed and arranged in juxtaposition.

Fig. 5 is a fragmentary side elevation of 65 one of the details of the invention.

Fig. 6 is a perspective view thereof.

Referring to the drawings by characters of reference 10 and 11 designate respectively the meeting ends of a pair of rails and 70 12 a pair of adjacent ties underlying the same. The supporting and connecting means include a pair of chair members 13, 13 of similar construction, a bridge plate 14, and angle bars 15, 15 of similar construction to 75 each other. The chair members are each constructed from a rectangular piece of material of a length slightly less than the width of the tie and of a width slightly less than the width of the base of the rail. Each 80

of the chair members is provided with a pair of spaced parallel longitudinally extending upstanding ribs 16 adapted to receive and embrace therebetween the rail base. The outer sides of said chair members are provided with spike-receiving openings 17 and 18, the latter passing through the ribs 16. One end of the portion of the chair member which lies between the ribs 16 is cut away 85 as at 19 and the said cutaway portion is provided with laterally extending recesses 20. The bridge plate 14 is provided with intermediately bulged side walls 21 each having an inwardly extending notch 22 centrally thereof. The opposite side walls of the ends 90 of the bridge plate converge and provide a reduced neck 23 having laterally extending ears 24 at the opposite sides of the extremity thereof. The upper surface of the bridge plate is longitudinally convexed as at 25, 100 and the under side of the same is provided with spaced parallel transversely extending ribs 26. The reduced necks 23 of the bridge plate are designed to be received by the cutaway portion 19 of the chair members 105 and the ears 24 are adapted to interengage with the recesses 20 of said cutaway portion. The chair members are designed to be arranged on the adjacent ties 12 which underlie the meeting ends 10 and 11 of the rails 110

with the opposite extremities of the bridge plate supported by said ties and the depending ribs 26 abutting the confronting side walls of said ties. Securing spikes 27 are driven through the spike-receiving openings 17 and 18 after the angle bars 15 have been secured by the bolts 28 to the opposite sides of the rail ends. The heads of the spikes which are driven into the openings 18 are received by the notches 29 in the angle bar and directly contact with the rail base. In order to prevent creeping of the rails longitudinally with relation to the supporting means, the lower flanges or aprons of the angle bars are provided with depending lugs 30 centrally thereof which are designed to be received by the notches 22 in the bridge plate. This arrangement locks the rails and angle bars 15 to the bridge plate 14 retained against longitudinal movement by the depending ribs 26, and the interengagement of the ears 24 with the recesses 20 of the chair members, which are in turn secured to the ties by the spikes, and the longitudinal convexity of the upper surface of the bridge plate illustrated at 25 insures a perfect alignment of the meeting ends of the rail to prevent relative vertical movements therebetween and affords a solid support therefor to prevent the sinking or sagging of the same.

It will thus be seen that a simple and efficient connecting and supporting means for the meeting ends of a pair of rails is provided which effectively supports the same, prevents creeping of the rails relative to the ties, which eliminates all possibility of spreading of the rails at this point, and which is comparatively inexpensive to produce and install.

Having thus described my invention, what I claim is:

1. Means for connecting and supporting the meeting ends of a pair of rails comprising chair members adapted to be secured upon adjacent ties, a bridge member having the opposite extremities thereof interengageably associated with the chair members, and angle bars secured to the opposite sides of the rail ends and interengageably associated with the bridge plate.

2. Means for connecting and supporting the meeting ends of a pair of rails comprising chair members adapted to be arranged on adjacent ties underlying the rail ends, longitudinally extending parallel ribs between which the rail bases are confined against lateral movement, a bridge plate interengageably associated at its opposite ends with the chair members and upon which the

60 rail ends are supported, angle bars traversing the opposite sides of the rail end, and

interengageable means respectively provided on the angle bars and the bridge plate for locking the same against relative longitudinal movements.

3. A rail joining and supporting means comprising angle bars traversing the opposite sides of the rails and clamped thereagainst, lugs depending from the angle bars at opposite sides of the rail base, a bridge plate supported at its opposite ends on the adjacent ties underlying said rail ends, the said plate having notches in its opposite sides adapted to receive the depending lugs of the angle bars for locking the rails and angle bars against longitudinal movement with respect to the bridge plate, and chair members respectively secured to said ties having parallel longitudinally extending ribs between which the rail bases are confined against lateral movement, the confronting ends of said chair members having cutaway portions adapted to receive and contact with the opposite ends of the base plate for locking the same against relative longitudinal movement with respect to the ties.

4. A supporting and connecting means for the meeting ends of a pair of rails including a bridge plate having its opposite ends supported by adjacent ties underlying said rail ends, depending transverse ribs respectively engaging the confronting sides of said ties, chair members interengageably associated with the opposite extremities of said bridge plate and secured to the ties, upstanding parallel longitudinal ribs on said chair members between which the rail bases are confined, angle bars traversing the opposite sides of said rail ends and secured thereto, and lugs depending from the angle bars at opposite sides of said rail bases, the said bridge plate having notches in its opposite sides adapted to receive said lugs for locking the rails against relative longitudinal movement.

5. The combination with the meeting ends of a pair of rails and supporting ties underlying the same, of means adapted for connecting said rails and supporting the same on the ties, comprising angle bars respectively secured to said rail ends at the opposite sides thereof having depending lugs, a bridge plate supported at its opposite ends by the ties and underlying said rail ends, notched portions in the opposite sides of said bridge plate receiving said depending lugs, and rail base embracing members secured to said ties and interengageably associated with the opposite extremities of the base plate.

JOHN HENRY JENNINGS.
